UNITED STATES PATENT OFFICE.

WILLIAM B. ALBURY, OF TAMPA, FLORIDA.

SLIP-COVER FOR AUTOMOBILE-TOPS.

1,193,961.

Specification of Letters Patent. Patented Aug. 8, 1916.

Application filed December 11, 1915. Serial No. 66,372.

To all whom it may concern:

Be it known that I, WILLIAM B. ALBURY, a citizen of the United States of America, residing at Tampa, in the county of Hillsborough and State of Florida, have invented 5 certain new and useful Improvements in Slip-Covers for Automobile-Tops, of which the following is a specification.

My invention relates to improvements in 10 slip covers for automobile tops.

Heretofore the slip covers for automobile tops have been opened along the sides and provided with buttons or fastenings which must be connected after the cover has 15 been slipped on in order to hold it securely in position at the sides. Due to the fact that the cover must be drawn tightly over the top to hold it securely in position and to give a neat appearance, there is a constant straining 20 at these buttons or fastenings, particularly in connecting them, that causes the cover to become quickly split and torn. From sixty to seventy-five per cent. of the covers that have come under my observation 25 have been split and torn beyond repair after from three to six months of daily use.

According to my invention I avoid splitting or tearing the sides of the cover by forming them for a fold or plait which has 30 fastened within it an elastic strip adapted to expand sufficiently to permit the cover to be drawn over the folded top in which position the elastic strip stretches until the sides of the cover are stretched taut, thus affording 35 a neat and attractive cover which will not become torn or split and, due to the protection from the weather afforded to the elastic side strips by the impervious outer sides of the cover, it will last as long as the 40 cover itself.

I have illustrated in the accompanying drawings what I regard as the preferred embodiment of my invention, wherein:—

Figure 1 is a side elevation of my cover 45 applied to a top. Fig. 2 is a perspective view of the cover broken away to show the elastic side bands; and Fig. 3 is an enlarged sectional view showing the cover with its elastic sides in relaxed and applied positions.

Similar reference numerals refer to similar parts throughout the drawings.

As illustrated, my invention is applied to

cover and protect the folding top 1 of an automobile 2, it being understood that the top may be of any well known design and 55 that my cover will be suited to such top when folded back. The cover comprises the top 3 and bottom 4 of any suitable water-proof material having the customary attaching flaps 5 and connected along the back and 60 side edges by a layer of water-proof material 6 forming the closed back and the outer side walls of the cover. It will be noticed that the side walls of the casing are made without openings and therefore it is 65 unnecessary to provide any fastenings, clasps or buttons. Instead of using the latter I attach within the cover along each side a strip or wide band of fabric 7, which strip is preferably attached to the cover by being 70 sewn along its top and bottom edges to flaps 8 which are inserted and stitched between the meeting edges of the side walls 6 and the top and bottom of the cover. The stitching 9 which passes through the corner edges of 75 the cover and the flaps 8 also serves to connect the binding strips 10 which gives the corners a neat, external finish. The elastic strip or band 7 is preferably formed of parallel strips of wide elastic webbing which 80 are suitably attached to each other along the side edges and at their ends to the flaps 8 or, where such is available, the elastic band may be made in one piece. The elastic band 7 is of such a width that in its relaxed position 85 it will hold the sides 6 of the cover drawn together and hanging in folds, as shown in full lines Fig. 3. In applying the cover, however, the side corners are grasped and the elastic bands 7 are stretched to the limit 90 and the cover is then slipped over the folded top and drawn forward into position, the side elastics holding it tightly and snugly about the top and leaving the sides with a smooth uninterrupted finish and free of 95 fastenings. If desired the elastic may be carried entirely around the sides and back but it is only necessary to be carried along the sides and it is of course preferable to protect it by the water-proof sides of the 100 cover which have the additional advantage of limiting the stretch to which the elastic can be subjected and thereby increasing its life.

Having thus described my invention, what I claim as new and desire to secure by Letters Patent, is:—

A slip cover for automobile tops formed of waterproof material and comprising a top, a bottom, a back and closed sides, and elastic webbing extending the length of the sides and attached along its top and bottom

edges to the top and bottom edges of the sides and adapted to be put under substantial tension when the sides are drawn taut. 10

In testimony whereof I affix my signature.

WILLIAM B. ALBURY.
